[57] CLAIM

The ornamental design for a smoothing tool for wall coverings, as shown.

DESCRIPTION

FIG. 1 is a perspective view taken from the top, front and left side of the smoothing tool for wall covering showing my new design;

FIG. 2 is a front elevational view thereof;

FIG. 3 is a top plan view thereof;

FIG. 4 is a bottom bottom plan view thereof;

FIG. 5 is a rear elevational view thereof;

FIG. 6 is a left side elevational view thereof; and,

FIG. 7 is a right side elevational view thereof.
